UNITED STATES PATENT OFFICE.

FRANK JOHNSON, OF AFTON, NEW YORK.

HORSE-COLLAR FASTENER.

SPECIFICATION forming part of Letters Patent No. 278,970, dated June 5, 1883.

Application filed April 5, 1883. (No model.)

To all whom it may concern:

Be it known that I, FRANK JOHNSON, a citizen of the United States of America, residing at Afton, in the county of Chenango and State 5 of New York, have invented certain new and useful Improvements in Horse-Collar Locks; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This invention relates to a lock for fastening together and permitting the separation of the upper ends of the two sides of a horse-collar, its object being to facilitate the placing and removal of the collar, and to provide there- 20 for a reliable and easily-operated fastening device.

The invention consists in certain novel constructions and combinations of devices, which will be readily understood from the following 25 description, with reference to the accompanying drawings, in which—

Figure 1 is a perspective view of my improved collar-lock with the two parts connected or locked together. Fig. 2 is a similar 30 view with the parts separated. Fig. 3 is a view of the lock provided with a modified form of latch.

Referring to Figs. 1 and 2, the letters A A' indicate curved plates adapted to be secured 35 to the upper ends of the two parts of a collar, respectively, the shanks a a' and a' a being adapted to be secured on opposite sides of the longitudinal indentations of the collar, and provided with suitable rivet-holes, b, and slots c to 40 receive rivets by which the plates may be secured to the inner leather of the collar. The plates A A' are respectively provided with flanges or face-plates B B', adapted to stand across the end edges of the two parts of the 45 collar. From the face-plate B of the plate A projects a bolt, D, provided with a transverse groove, E, and having its outer end beveled on its outer surface, as shown at d. In the face-plate B' of the plate A' is formed a slot, 50 C, adapted to receive the bolt D, which will project therein sufficiently to carry its groove E behind the face-plate B'. To the rear side

of this face-plate B' is hinged a latch, F, provided with a notch, f, which coincides with the slot C. This latch F is pivoted to the rear side of the face-plate B' at one end of the slot C, and has its pivoted end provided with an extension, G, which forms a thumb-piece under which is arranged a spring, H, one end of which bears against the plate A' and the other 60 against the thumb-piece, so that thereby the latch will be held normally in its closed position, as shown in Fig. 1, at which time the intermediate portion of the latch engages with the groove E of the bolt and prevents the latch from being withdrawn. By pressing upon the thumb-piece G the latch will be raised out of engagement with the bolt, so that the latter may be withdrawn and the two parts of the 65 lock separated.

The letter k designates a lug which projects from the plate A' on the rear side of the latch and prevents said latch from being forced laterally by the bolt D when the latter is inserted in the slot C.

The operation of the lock will be readily understood. When the bolt is inserted in the slot C the beveled face d strikes and forces upward the latch, which falls into the groove E so soon as the face-plates come together, and holds them in that position. To separate the two parts of a collar it is only necessary to press the thumb upon the thumb-piece G and withdraw the bolt from the slot C.

In the modification shown in Fig. 3 the thumb-piece is dispensed with, and at its opposite end the latch is provided with an endwise projection, l, by which it may be operated. A spring-lug, m, bears against the rear side of this latch and holds it in position by friction.

By providing the plates A and A' with the slots c c', through which rivets may pass, I am enabled readily to adjust the plates by simply removing the rivets from their rear ends and sliding the plates either way without removing the rivets from the slots, the end rivets being replaced when the plates are properly adjusted.

Having now fully described my invention, I claim—

1. A horse-collar lock composed of the two plates A A', adapted to be secured to the two parts of a collar, the plate A being provided with a face-plate, B, having a projecting bolt,

D, and the plate A' having a face-plate, B', provided with a slot to receive and a latch to engage said bolt, substantially as described.

2. The combination, with the plate A, having the face-plate B and transversely-grooved bolt D, of the plate A', having the face-plate B', provided with the slot C to receive said bolt, and the spring-actuated latch F, pivoted behind said face-plate B' and arranged to engage 10 said bolt, substantially as described.

3. The combination, with the plate A', having the slotted face-plate B', of the spring-latch F, pivoted behind said face-plate, and provided with the thumb-piece G, and the spring arranged under said thumb-piece, substantially 15 as described, and for the purpose set forth.

4. The combination of the plate A', provided with the lug k and face-plate B' and latch F, arranged to prevent said latch from being forced laterally rearward, substantially as described. 20

5. In a collar-lock, the plates A and A', provided with the rivet-slots c near their front ends, and the rivet-holes near their rear ends, substantially as described.

In testimony whereof I affix my signature in 25 presence of two witnesses.

FRANK JOHNSON.
